UNITED STATES PATENT OFFICE.

HENRY SLUSHER, OF INDIANAPOLIS, INDIANA.

PENDULUM-GUARD.

SPECIFICATION forming part of Letters Patent No. 251,648, dated December 27, 1881.

Application filed October 6, 1881. (No model.)

To all whom it may concern:

Be it known that I, HENRY SLUSHER, of the city of Indianapolis, county of Marion, and State of Indiana, have invented certain new and useful Improvements in Pendulum-Guards, of which the following is a specification.

The object of my said invention is to produce a device which shall guard the limber portion of the pendulum-rod of a clock from being bent or kinked by being forced out of its ordinary or proper position; and it consists of a guard-rod attached to the pendulum rod just below its limber portion and running upwardly until it comes nearly in contact with the stud or pin in the frame-work on which the pendulum is hung, or with a separate pin, as will hereinafter be more specifically set forth.

Referring to the accompanying drawings, which are made a part hereof, and on which similar letters of reference indicate similar parts, Figure 1 is a front elevation of a clock to which my invention is applied, so much of the door and face being broken away as is necessary to bring it into view; Fig. 2, a detail elevation of the improvement on an enlarged scale; Fig. 3, a vertical section thereof on the dotted line *xx*; and Fig. 4, an under side view of the pin *B* and surrounding parts, as seen when looking upwardly from the dotted line *yy*.

In said drawings the portion marked *A* represents the usual pendulum-rod of the clock, having the usual limber portion, *a*; *B*, the stud or pin to which said pendulum is attached; and *C*, the guard-rod attached to the pendulum-rod, preferably just below its limber portion, and extending upwardly until it comes nearly in contact with the pin *B*. A cross-bar, *C'*, is preferably attached to the top end of this guard-rod, or is formed in piece therewith, and its ends *c' c'* should be turned upwardly to partly surround the stud *B* and prevent the parts from becoming disengaged.

As will be readily seen, the pendulum-rod can be pushed upwardly only a very short distance when this device is employed, and therefore the limber part cannot be kinked or bent, and a prevailing source of annoyance is thus avoided, as unskilled persons are very apt to bend this limber portion in their manipulations of the pendulum when it is not protected in this manner.

Instead of running the guard-rod *C* up to the pin *B*, it may be made in the form of a cross-bar, and a pin inserted in the frame-work of the clock just above it, which will serve the same purpose in this connection as the form shown. I regard the latter, however, as much the best, but regard both forms as included in my invention. The said alternate construction is illustrated in Fig. 5 of the drawings, which has not been heretofore mentioned.

Having thus fully described my said invention, what I claim as new, and desire to secure by Letters Patent, is—

1. The combination, with the pendulum-rod of a clock, of the guard-rod *C*, which extends up in close proximity to the stud or pin *B*, substantially as described, and for the purpose specified.

2. The combination, with the pendulum-rod of a clock, of a guard rod or bar and a stud or pin, said guard rod or bar having upturned ends, substantially as shown and described, and for the purpose specified.

In witness whereof I have hereunto set my hand and seal, at Indianapolis, Indiana, this 3d day of October, A. D. 1881.

HENRY SLUSHER. [L. S.]

In presence of—

C. BRADFORD,
C. DUVALL.
